UNITED STATES PATENT OFFICE.

LYMAN O. GOODWIN, OF NORTH ANDOVER, MASSACHUSETTS, ASSIGNOR TO
HIMSELF AND GEORGE L. WRIGHT, OF SAME PLACE.

DESIGN FOR A VALVE FOR GOVERNORS.

SPECIFICATION forming part of Design No. 34,717, dated July 2, 1901.

Application filed February 7, 1901. Serial No. 46,443. Term of patent 14 years.

To all whom it may concern:

Be it known that I, LYMAN O. GOODWIN, a citizen of the United States, residing at North Andover, in the county of Essex and State of Massachusetts, have invented a certain new, useful, and original Design for a Valve for Governors, of which the following is a specification, reference being had therein to the accompanying drawings.

16 In the drawings, Figure 1 represents a view in side elevation of a valve illustrating my new design. Fig. 2 represents an end view of the same.

The leading feature of my new design for 15 valves for governors consists in the design as herein shown and described.

As shown in the drawings, the valve has the generally cylindrical surface 5, broken by the longitudinal openings 6 6, having the sides 7 20 and 7' extending from the surfaces 8 8, forming the end walls of said openings, to the end

9 of the valve-body. Between the openings 6 6 is the oblong opening 10, extending transversely through the valve-body. At the end opposite that marked 9 is the annular flange 25 11, larger in diameter than the valve-body, and axially disposed on this flange is the stem 12. The end view of the valve discloses the sides 7' 7' of the openings 6 6 as extending to the surfaces 13 13, which surfaces are connected by the curves 14 14 and 15 15 with the sides 7 7 of said openings.

What I claim is—

The design for a valve for governors as herein shown and described.

In testimony whereof I affix my signature in presence of two witnesses.

LYMAN O. GOODWIN.
